UNITED STATES PATENT OFFICE.

JAMES A. MOULD, OF MILWAUKEE, WISCONSIN, ASSIGNOR TO EVINRUDE MOTOR COMPANY, OF MILWAUKEE, WISCONSIN.

WATER-SUPPLY CONNECTION.

Application filed January 7, 1924. Serial No. 684,720.

To all whom it may concern:

Be it known that I, JAMES A. MOULD, a citizen of the United States, residing at Milwaukee, county of Milwaukee, and State of

5 Wisconsin, have invented new and useful Improvements in Water-Supply Connections, of which the following is a specification.

This invention relates to improvements in 10 water-supply connections for outboard motors of the type in which reversal is accomplished by a bodily rotative movement of the propeller and related parts about the axis of the upright driving shaft therefor.

15 It will be understood that the ordinary outboard motor includes an internal combustion engine, the power of which is transmitted through a vertical drive shaft to a horizontal propeller shaft and a propeller 20 carried thereby. The propeller shaft and propeller, together with gearing for connecting the propeller shaft and drive shaft, are usually supported by means of a tubular housing for the vertical drive shaft. Such 25 an arrangement of parts is shown in the patent to Evinrude, No. 1,001,260, dated August 22, 1911.

It has always been more or less of a problem to provide water for the cooling of an 30 internal combustion engine such as is disclosed in the above mentioned patent. This problem is intensified when the construction of the outboard motor includes a bracket having rearwardly projecting arms for the

35 adjustment of the motor in a vertical plane while preserving the rotative character of the drive shaft housing. Such a bracket is disclosed in Patent No. 1,236,735, issued to C. J. Meyer, August 14, 1917.

40 It will be understood that if water supply connections are led from a point beneath the water line to the cylinders of the motor, it is not only possible but probable that such connections may become entangled with the arms of the 45 bracket and may become broken or otherwise damaged.

Various expedients have been devised in an attempt to overcome the difficulties above noted, but, so far as I am aware, all of 50 such expedients have involved constructions

which were either complicated, difficult to construct, expensive to manufacture, or so heavy as to add unnecessary weight to the device.

It is the primary object of this invention 55 therefore to provide a novel and direct water connection between a submerged pump and the engine cooling jacket and to lead such connection past a bearing at the bracket arms above referred to without a complicated, expensive, or heavy construction.

More specifically stated, it is the object 60 of this invention to provide a water supply connection within the radius of the drive shaft housing and yet exterior to said housing so that the water pipe will be accessible 65 for its initial placement, replacement, or repair, and will not be subject to damage by frictional contact with the drive shaft.

Another difficulty heretofore experienced 70 with such water supply connections as have been introduced into the interior of the drive shaft housing has consisted in the possibility of water leakage occurring to dilute lubricant in the propeller gear case supported by 75 said housing. It is, therefore, an object of this invention to lead the water pipe through a bearing which receives said housing without using a construction requiring the perforation of the housing. As will appear hereinafter, the device herein disclosed is so constructed that the drive shaft housing is imperforate throughout its length and is therefore not subject to water leakage.

80 In the drawings:

Figure 1 is a diagrammatic view in side elevation of an outboard motor embodying the present invention.

Figure 2 is a vertical longitudinal section through a portion of the drive shaft 90 housing and water supply connections of the outboard motor illustrated in Figure 1, portions of the housing and connection being broken away to foreshorten the view.

Figure 3 is a section taken on line 3-3 95 of Figure 2.

Figure 4 is a section taken on line 4-4 95 of Figure 2.

Figure 5 is a side elevation of a modified construction of the bearing block and shaft 100

housing, the parts being broken away to an axial vertical section to expose their interior construction.

Figure 6 is a section taken on line 6—6
5 of Figure 5.

Like parts are identified by the same reference characters throughout the several views.

As indicated above, the outboard motor 10 to which this invention is applicable is of the general type illustrated in the patent to Evinrude, No. 1,001,260. The motor will, therefore, be described but briefly herein.

The device includes an engine of which 5 15 represents the jacketed cylinder, 6 the crank case, and 7 the fly wheel. The engine is supported for pivotal movement in a vertical plane about the pivot pin 8 which connects it with bracket 9. This bracket is 20 adapted to engage the transom of a boat in the usual manner and is provided with a downwardly extending portion 10 from which project rearwardly the spaced arms 11.

25 Connected with the fly wheel 7 is an upright drive shaft 12 which extends downwardly between arms 11 and is encased by a tubular shaft housing 13 which likewise extends between said arms and finds a bearing 30 in a block 14 which is adjustable between the arms to a plurality of predetermined positions, whereby to control the angular setting of the motor upon its supporting pivot pin 8.

The shaft housing 13 supports a propeller gear casing 16 within which is journaled 35 a propeller shaft 17 for the support of propeller 18. The housing 16 carries a pump casing 19 having an inlet portion 20, the pump plunger being preferably driven by a 40 cam on vertical drive shaft 12 after the manner disclosed in the application of James A. Mould, filed March 5, 1923, Serial No. 622,739. The particular construction of the pump is unimportant, however.

45 The delivery pipe 22 of the pump extends upwardly therefrom and thence radially inwardly toward the housing 13. It will be understood that this housing and all related parts, including the pump, are not only 50 mounted for oscillation upon a vertical axis responsive to the movements of tiller handle 24 but also that the housing and the submerged parts carried thereby may be rotated bodily through 180° independently of the 55 tiller upon their release from the tiller through some mechanism similar to that disclosed in the patent to C. J. Meyer, No. 1,191,211, of July 18, 1916. With such mechanism, when it is desired to operate the 60 motor in a forward direction after it has once been reversed, the housing is again released and travels through an additional 180° arc, thereby completing a single revolution about the vertical axis of the drive shaft. Under such circumstances it will be

obvious that unless special provision is made to lead the water pipe past bearing block 14 such pipe would become hopelessly entangled in the block or in the arms 11.

In the preferred embodiment of this invention, the wall of shaft housing 13 is longitudinally indented to provide a vertically extending groove such as that indicated at 25. This groove is made of sufficient depth to receive bodily a pipe 26 so that the exterior wall of the pipe is wholly within the circumference of a circle including the undented portions of the wall of the housing. In other words, the tube 26 is located wholly within the radius of the housing wall.

At the lower end of the inlaid tube 26, the longitudinal channel, shown at 25 to receive said tube, is preferably filled about the tube by solder, or otherwise, in the manner indicated at 27 in Figure 3. Secured about the shaft housing at this point is a two-part clamp, including the generally semi-circular elements 28 and 29, which may conveniently be held together by cap screws such as that shown at 30. The solder which is filled into channel 25 about the lower end of tube 26 will make a water-tight joint between the end of said tube and the clamp. Suitable packing may be interposed between clamp section 29 and the solder at 31, if desired. The lower portion of clamp section 29 will preferably bear, through the packing 31, directly upon the wall of housing 13, no solder being necessary at that point.

100 Clamp section 29 may be provided with a nipple 32 adapted to receive the inwardly directed end of pipe 22, and have threaded thereto a nut 33 for effecting the usual coupling between these parts. Thus, the water delivered from pump casing 19 is directed into a vertical pipe 26, which is not only wholly within the radius of the shaft housing wall, but is nevertheless external to the indented portion of said wall so that it is very readily accessible and can easily and cheaply be set in place.

105 Attached to the crank case 6 is a housing 35 which contains the latch mechanism for the release of shaft housing 13 for reversing purposes. Extending downwardly from housing 35 is a sleeve 36 which provides a bearing for the supporting member 37 which carries the entire motor from pivot pin 8. Sleeve 36 extends through the supporting member and is enlarged at 38 and internally cored out to provide a water chamber 39, closed at its lower end by a packing nut 40 which may be threaded to the sleeve portion 38 as indicated.

110 It will be noted that the channel 25 in shaft housing 13 extends well upwardly into the sleeve portion 38. The channel about the upper end of tube 26 is preferably filled in with solder in the manner indicated at 27

in Figure 3. Within chamber 39 is a lantern ring or annulus 42 provided with apertures at 43 for water delivery therethrough. This annulus divides chamber 39 into two concentric compartments, the inner of which is adapted to receive water directly from tube 26 and the outer of which is adapted to deliver such water through port 44 to the pipe 45 which leads from sleeve portion 38 to the cylinder jacket. Packing may be used at 46 and 47, if desired, to ensure that the joints on either side of the lantern ring 42 will be tight.

As has already been indicated, the sleeve portion 38 is directly connected with the crank case and thereby with the cylinders so that the pipe 45 may be wholly inflexible. These parts all oscillate together within the supporting member 37 for steering purposes, and the shaft housing 13 is released through the mechanism in housing 35 for independent rotation when it is desired to reverse the motor. At such times as the motor is in reverse the tube 26 will deliver water to the opposite side of lantern ring 42 so that such water will have to traverse 180° of compartment 39 before reaching the outlet port 44.

In Figures 5 and 6 I have illustrated another modified construction, showing an application of this invention to a known structure. Figures 5 and 6 show a construction which is disclosed in the co-pending application of James A. Mould, executed of even date herewith, and entitled "Anti-tilting lock for reversible outboard motors." In this construction a semi-tubular bearing block 50 takes the place of bearing block 14. The semi-tubular bearing block 50 opens rearwardly as is clearly shown in Figure 6. It is provided with an upwardly extending ear 51 provided with an aperture 52, whereby the bearing block may be positioned at any desired point between arms 11. At its upper end the bearing block 50 is provided with a concentric enlarged portion 53 upon which is fastened a semi-annular cap 54 having a depending sleeve 55 immediately adjacent the shaft housing 13. Clamped to the shaft housing 13 is a sleeve 57 axially cut at 58 and provided upon either side of the cut with ears such as that which is shown at 59. By means of these ears, which are apertured at 60, a bolt may be utilized to clamp the sleeve in any desired position upon the shaft housing. The sleeve carries at its upper and lower ends annular flanges 62 and 63, respectively. As disclosed in the application above referred to, means is provided for lifting the entire shaft housing, with the shaft and operating parts, at the moment the shaft housing and related parts are released for independent rotation for reversing purposes. When the shaft housing is thus lifted the sleeve 57, being clamped thereto, will be lifted therewith and the annular flange 62 will be engaged with the relatively stationary semi-sleeve 55 carried by block 50. The flange 63 will simultaneously engage the lower end of the semi-tubular block. Due to this engagement, which is effected at the moment of reversal, the motor is prevented from being tilted by the rearward thrust of the propeller, although, with the parts in the position indicated, the motor is free to tilt if a submerged obstacle is encountered. It will be noted that the construction illustrated corresponds, so far as the disposition of tube 26 is concerned, with that disclosed in Figure 2, the principal difference being that the bearing surface between the shaft housing and block 50, instead of being formed directly upon the shaft housing, is formed upon the sleeve 57 carried by the shaft housing and, to all intents and purposes, a part thereof.

In view of the fact that the above construction is disclosed more particularly in the application in which it is claimed, it is not thought necessary to go into further detail herein. It is merely desired to bring out that where a supplemental bearing block, such as that shown at 57, is employed, and which is not of sufficiently greater radius that the shaft housing to permit it to carry tube 26 exterior of the shaft housing, the tube may be located within the groove or depression of the shaft housing in the manner indicated in Figures 5 and 6.

It will be clear from the foregoing description that all of the devices herein disclosed are extremely easy of application while accomplishing effectively the purposes for which they are designed. Each device is adapted to make possible the use of standard parts, and each device is adapted to lead the water pipe through a bearing in block 14, or 50, without danger of entangling the water supply connections in the arms 11 during motor reversal. The disposition of the water pipe illustrated in Figures 1 to 6, inclusive, is such, furthermore, that it not only enables the use of a standard bearing block at 14 (or at 50) and a bracket having arms 11 spaced at the usual distance apart, but also makes it possible to dispose tube 26 in such a position that it is fully protected from the danger of injury or entanglement with objects encountered in the water. When it is remembered that boats having outboard motors are frequently operated in shallow streams and in waters where snags and submerged obstacles abound, the importance of a construction in which the water supply connections are protected against entanglement will be obvious.

I claim:

1. In a device of the character described, the combination with a support for the sub-

merged parts of an outboard motor mounted for rotation and provided with a central cavity, of a bearing block disposed at an intermediate portion of said support, said support being formed with an arcuate bearing surface adapted for operative bearing contact with said block, and a water supply pipe extending along said support externally of the cavity therein wholly at one side of the cavity and within the radius of said bearing surface.

2. In a device of the character described, the combination with a hollow support for the submerged parts of an outboard motor and a drive shaft extending through said support, of a pipe extending along said support externally of the hollow portion thereof and wholly at one side of said shaft, said pipe being encompassed forwardly and laterally only by portions of said support, and being exposed at its rearward side whereby it is protected against injury and is nevertheless accessible for placement and removal.

3. In a device of the character described, the combination with the parts of an outboard motor adapted to be submerged when in use, of a support for said parts provided externally with a longitudinally extending indented channel, together with a part requiring protection and extending longitudinally of said support along said channel, whereby to be protected by said support.

4. In a device of the character described, the combination with a rotatable tube having a longitudinally channeled indented wall, of a pipe set within the indented portion of said wall.

5. In a device of the character described, the combination with a rotatable tube having at an intermediate portion a peripheral bearing surface and provided in its wall with an indented portion extending across said surface, of a bearing block provided with a surface complementary to that of the tube, and a pipe traversing the bearing surface of the tube exterior to the indented portion of the wall thereof, said pipe being wholly within the radius of the bearing portion of said tube.

50 6. In a device of the character described, the combination with a rotatable support for the submerged parts of an outboard motor, of a bracket provided with arms embracing said support, said support being provided with an arcuate bearing surface complementary to that of the block and having a

longitudinally extending groove traversing said surface, a pump connected with said support below said arms, and a discharge pipe for said pump extending along said groove between said arms.

7. In a device of the character described, the combination with an engine having a jacketed cylinder and supported for oscillation about an upright axis, of a shaft extending downwardly from said engine, a housing for said shaft rotatable independently of said engine and provided with an arcuate bearing surface, a bearing block having a complementary surface and having portions embracing said housing, a longitudinally extending pipe immediately adjacent said housing externally thereof and disposed within the radius of the bearing surface thereof, a pump arranged for delivery to said pipe below said block, and a distributing chamber including portions connected respectively to said engine cylinder and to said housing for relative rotation, said pipe being adapted for delivery through one of said chamber portions, whereby the output of said pump may be led toward said cylinder irrespective of relative rotation between said housing and said cylinder and said block.

8. In a device of the character described, the combination with a rotatable shaft housing having a longitudinally indented wall, of a pipe disposed within the indentation of said wall, a fitting attached to said housing at one end of said indentation and provided with an inlet port, means for filling said indentation between said housing, said pipe and said fitting, and a duct connected to said port.

9. In a device of the character described, a tubular support for the parts of an outboard motor submerged when in use, said support comprising a member of generally tubular cross section having its wall longitudinally indented to produce an arcuate channel, said channel being of a depth to receive bodily water supply connections and being wholly at one side of the longitudinal axis of said support, whereby to provide a longitudinal opening within said support for a drive shaft and to provide externally of said support, and in protective relation thereto, sufficient space for water supply connections.

JAMES A. MOULD.
